UNITED STATES PATENT OFFICE

148,018

DESIGN FOR A WHEELBARROW

Henry T. Free, Shawnee, Kans., and James P. Robertson and Steven Merz, Kansas City, Mo.

Application June 17, 1946, Serial No. 130,772

Term of patent 3½ years

(Cl. D14—3)

To all whom it may concern:

Be it known that we, Henry T. Free, James P. Robertson, and Steven Merz, citizens of the United States, residing at Shawnee, in the county of Johnson, State of Kansas; Kansas City, in the county of Jackson, State of Missouri; and Kansas City, in the county of Jackson, State of Missouri, respectively; have invented a new, original, and ornamental Design for a Wheelbarrow, of which the following is a specification, reference being had to the accompanying drawing, forming a part thereof.

Figure 1 is a perspective view of the wheelbarrow, showing our new design; and

Fig. 2 is a top plan view thereof.

The dominant features of the design reside in the portions shown in full lines.

We claim:

The ornamental design for a wheelbarrow, as shown and described.

HENRY T. FREE.

JAMES P. ROBERTSON.

STEVEN MERZ.
